(57) CLAIM

The ornamental design for a tool bag, as shown and described.

DESCRIPTION

FIG. 1 is a perspective view of a tool bag showing our new design.

FIG. 2 is a front view thereof.

FIG. 3 is a first side view thereof.

FIG. 4 is a second side view thereof.

FIG. 5 is a back view thereof.

FIG. 6 is a top view thereof.

FIG. 7 is a bottom view thereof; and,

FIG. 8 is a top view of the tool bag, shown in an alternate configuration with the top flap open and the side zippers open.

The broken lines shown in the drawings are for the purpose of illustrating portions of the tool bag that form no part of the claimed design.

1 Claim, 8 Drawing Sheets
